GARMENT BAGGING MACHINE

Harlyn D. Oliver, Detroit, Mich.

Application March 11, 1936, Serial No. 68,293

26 Claims. (Cl. 226—18)

My invention relates to improvements in a garment bagging machine in which a bag is applied over a garment while supported on the machine and the objects of my improvements are, first, to provide a garment bagging machine which will be more rapid and convenient in its operation than heretofore possible; second, to provide a garment bagging machine utilizing an endless belt for conveying the bag to a position for ready placement over the garment; third, to provide a garment bagging machine adapted to utilize bags of different length without the necessity of making adjustments therefor; fourth, to provide a garment bagging machine with power operated means for moving a bag to a position ready for placement over the garment; fifth, to provide a garment bagging machine having power operated means for moving a bag to a position of placement over the garment with means for permitting an operator to control the operation of the power operated means from a sole point; sixth, to provide a garment bagging machine in which a plurality of bags may be operated simultaneously, by a sole power means, to positions of placement from where each bag may be applied over a garment; seventh, to provide a garment bagging machine utilizing an endless belt for conveying a bag to a position for placement over a garment with means for detaching the bag from the endless belt; eighth, to provide a garment bagging machine with a tubular housing for enclosing a belt for conveying a bag to a position over the tubular housing for placement over the garment; ninth, to provide a garment bagging machine having a lubricant tight compartment for torque transmitting mechanism driven by power means; tenth, to provide a garment bagging machine with means for adjustably supporting it from a wall structure; eleventh, to provide a garment bagging machine having adjustable means for supporting it from a ceiling structure with support means adapted to attach to said adjustable means to render it adaptable for supporting the garment bagging machine from a vertical wall structure; twelfth, to provide a garment bagging machine with bag conveyor means oppositely disposed about a drive shaft; thirteenth, to provide a garment bagging machine having bag conveyor means with switch means for automatically stopping movement of said bag conveyor means when the bag has been conveyed to a position for placement over the garment; fourteenth, to provide a garment bagging machine with a head assembly having separate compartments for torque transmitting mechanism and

power means for driving the torque transmitting mechanism; fifteenth, to provide a garment bagging machine having bag conveyor means solely exposed at one of its sides for attaching the bag to the conveyor means; and sixteenth, to provide a garment bagging machine having bag conveyor means with switch means adapted to stop the operation of power means utilized for driving the conveyor means, the switch means being actuated by the bag conveyor means.

I attain these objects by the mechanism illustrated in the accompanying drawings, in which:

Figure 1 is a side view of the garment bagging machine supported from a ceiling and with one of its head cover members and one of its belt housings partially broken away; Fig. 2, a sectional view of the garment bagging machine disclosed in Fig. 1, said sectional view being taken on the line 2—2, Fig. 1; Fig. 3, a partial sectional view of the garment bagging machine taken on the line 3—3, Fig. 1, said sectional view omitting the cover members for the main housing; Fig. 4, a sectional view of the garment bagging machine taken on the line 4—4, Fig. 3; Fig. 5, a partial plan and sectional view of the garment bagging machine taken on the line 5—5, Fig. 4; Fig. 6, an enlarged sectional view of one of the belt housings together with belt and switch mechanism taken on the line 6—6, Fig. 2, said sectional view being taken to disclose a bag therewith for enclosing a garment; Fig. 7, a partial sectional view of the tubular housing and belt and switch mechanism disclosed in Fig. 6, said partial sectional view being taken on the line 7—7, Fig. 6; Fig. 8, a partial side and sectional view of the tubular housing together with the belt and switch mechanism disclosed in Fig. 6, said partial side and sectional view being taken on the line 8—8, Fig. 6; Fig. 9, a partial side and sectional view of one of the belts and one of its clips for holding a bag together with a partial side view of a bag therein; Fig. 10, a sectional view of the belt and clip together with the bag disclosed in Fig. 9, said sectional view being taken on the line 10—10, Fig. 9; Fig. 11, a side view of a lever member of the switch mechanism; Fig. 12, an end view of the lever member disclosed in Fig. 11; Fig. 13, a view of the opposite end of the lever member disclosed in Fig. 11; Fig. 14, a side view of a lever bushing; Fig. 15, an end view of the lever bushing disclosed in Fig. 14; Fig. 16, a sectional view of one of the tubular housings on the line 16—16, Fig. 1; Fig. 17, an end view of one of the tubular housings as viewed from the line 17—17, Fig. 1; Fig. 18, a side view of one of the trip levers for operating

the switch mechanism; Fig. 19, a side view of the trip lever disclosed in Fig. 18; Fig. 20, a longitudinal sectional view of one of the switch buttons; Fig. 21, a rear view of the switch button disclosed in Fig. 20; Fig. 22, a front view of a terminal block; Fig. 23, a side view of the terminal block disclosed in Fig. 22; Fig. 24, a front view of an insulator block; Fig. 25, a side view of the insulator block; Fig. 26, a front view of a terminal member; Fig. 27, a side view of the terminal member disclosed in Fig. 26; Fig. 28, a sectional view through one of the belt pulleys taken on the line 28—28, Fig. 1; Fig. 29, a sectional view through one of the conveyor belt pulleys taken on the line 29—29, Fig. 3; and Fig. 30, a view disclosing my garment bagging machine mounted on a vertical wall.

Similar numerals refer to similar parts throughout the several views.

20 The garment bagging machine is provided with the head assembly A together with the belt housing assemblies B and C supported therefrom. The head assembly A comprises the wall structure 1 extending upwardly from the base portion or flange 2 and the base portion or flange 3 extending on the opposite side from the wall structure 1, the flange 2 extending at its lowermost portion in a plane located above the plane in which the lowermost portion of the flange 3 extends. The electric motor assembly D is mounted on and suitably secured to the boss 4 on the flange 3, the electric motor assembly D being electrically connected to a source of electric supply by the cable 5 which extends through the opening 1A in the wall structure 1 to suitable terminals electrically connected with switch mechanism herein-after more fully disclosed.

40 The drive shaft 1 of the electric motor assembly D is connected to the shaft extension 8 by the coupling mechanism 9, the shaft extension 8 forming an integral portion of the worm shaft 10 which is provided with the worm 11 which engages with and drives the worm gear 12.

The wall structure 1 is provided with the bore 45 13 in which is mounted the thrust bearing assembly 14 for rotatably supporting one end of the worm shaft 10, the worm shaft 10 being supported at its other end by the thrust bearing assembly 15 mounted in the bore 16 of the wall structure 17 extending upwardly from the flange 2.

50 The thrust bearing assemblies 14 and 15 are respectively retained by the retainer members 18 and 19 which are threadably mounted in the bores 13 and 16 of the wall structures 1 and 17. The worm gear 12 is mounted on the shaft 19 and is secured by the key 20 to turn therewith, the spiral bevel gears 21 and 22 being respectively secured on the ends of the shaft 19 by the keys 23, the washers 24A and nuts 24.

60 It is to be noted that the wall structures 1 and 17 extend upwardly from the flange 2 and are connected across their ends by the wall portions 25, as disclosed in Fig. 1, the wall portions 25 extending upwardly to permit the wall portions 25 together with the wall structures 1 and 17 to be provided with the flange portion 26 extending therearound with its upper surfaces located in a horizontal plane extending substantially through the centers of the worm gear 12 and the spiral gears 21 and 22 to permit the cover member 27, together with its flange portion 28 extending therearound to be mounted on the flange portion 26 to provide a closed chamber 29 formed by the wall structures 1 and 75 17, the wall portions 25, together with the cover

member 27, said closed chamber 29 being adapted to contain lubricant for properly lubricating the various gears operating in said chamber 29.

A gasket or shim, or plurality of gaskets or shims 30 may be interposed between the cover member 27 and the flange 26 to provide proper adjustment for positioning the worm gear 12 and the spiral bevel gears 21 and 22 respectively relative to the worm 11 and the spiral bevel gears 31 and 32.

10 It is also to be noted that the cover member 27 is provided with the portions 33, 34, and 35 to conform to the shape of the gear members extending thereinto.

15 It is also to be noted that the cover member 27, together with the caps 38, will be provided with cylindrical bores 36 extending therethrough to permit the bushings 37 to be assembled therein to provide bearings for the shaft 19 intermediate the worm gear 12 and each of the spiral bevel gears 21 and 22, the caps 38 being secured by the screws 38A.

20 The cover member 27, together with the gasket or shim means 30 is secured to the flange portion 26 by the screws 63.

25 The spiral bevel gears 31 and 32 which are respectively driven by the spiral bevel gears 21 and 22 are each mounted on the shafts 39 which are secured by keys 40 to turn therewith, the shafts 39 being supported on opposite sides of the gears 31 and 32 by the bearing assemblies 41 and 42, the bearing assemblies 41 and 42 being respectively mounted in the bores 43 and 44 of the wall structures 1 and 17, the bearing assemblies 41 and 42 being fixedly retained by the retainer members 45 and 46.

30 It is to be noted that the retainer member 46 together with the retainer members 48 will each be provided with a suitable packing material 47 to prevent lubricant from escaping from the chamber 29.

35 It is to be now noted that the wall structure 1 will be provided at each of its oppositely disposed sides with the boss portions 48 each of which are provided with a bore 49 through which extend the shafts 50 which are suitably secured to the hub members 51 as by welding, brazing or similar means, the hub members 51 each being provided with the flange 52 which is adapted to be secured to the ceiling wall 6 by the screws 53.

40 The shafts 50 are provided with a plurality of indexed notches 54 which are adapted to be engaged by the ends of the screws 55 each provided with the handle portion 56, the screws 55 threadably engaging the boss portions 48 to lock the head assembly A in any desired position on the shafts 50, thus providing for any adjustment for the head assembly A together with its supported mechanism in an up and down direction relative to the ceiling wall 6.

45 Figs. 1, 2, 3 and 4 disclose my garment bagging machine as being mounted on the ceiling wall 6 and relative to which the garment bagging machine may be adjusted in an up and down direction to obtain various operating positions relative thereto in order to provide the proper operating position for the operator and relative to a floor upon which the operator stands, it being possible to provide the shafts 50 in a series of lengths to permit my garment bagging machine to be readily assembled to ceiling walls 6 of various heights and at the same time to provide a reasonable range of adjustment for the garment bagging machine to permit operation with 50

garment bags of different lengths and for operators of different heights.

Fig. 30 discloses my garment bagging machine mounted on a vertical wall surface 57 which thus adapts it to be readily supported from a side wall of the room when desired.

The bracket 58 is provided with the flange 59 which is adapted to fit against the wall surface 57 and to be secured thereto by the screws 60. The bracket 58 is further provided with the bosses 61 which are adapted to be engaged by the flanges 52 of the hub members 51 and to be secured thereto by the screws 53, thus permitting the garment bagging machine, as designed for mounting on the ceiling wall surface 6, to be readily adapted for mounting on the vertical wall surface 57 by utilizing the bracket 58 as an auxiliary unit without changing the supporting mechanism of the original garment bagging machine.

The bracket 58 is further provided with the rib or web member 62 to provide requisite strength for supporting the bagging machine.

It is to be noted also that whereas I have disclosed the bracket 58 as being mounted on a side wall surface 57 extending in a plane located at right angles to a vertical plane extending through the axes of the shafts 50, it is to be understood that the flange 59 may be positioned for securement to a vertical wall surface located in a plane extending parallel with said vertical plane extending through the axes of the shafts 50.

It is also to be noted that the flanges 2 and 3 will be provided at their sides with the upwardly extending and curved wall portions 64 which will be provided with the notches or shoulder portions 65 for positioning the cover members 66 and 67, the notches or shoulder portions 65 being extended around the ends of the flanges 2 and 3, as at 68 and 69.

Also the wall structure 1 will be provided with the shouldered surfaces 71 and 72, the shouldered surfaces 65, 68, 69, 71 and 72 permitting the cover members 66 and 67 to be positioned on and form means for covering and enclosing the upper portions of the head assembly A, thus providing means whereby the operating mechanism of the head assembly A may be protected from dirt and similar foreign matter, and at the same time to provide a pleasing shape and smooth contour of the head assembly A, thus not only protecting the operating mechanism therefor but enhancing the appearance of my garment bagging machine for use in dry cleaning establishments, laundries and similar institutions and department stores, for which my garment bagging machine is particularly adapted, as well as rendering the operating mechanism of the head assembly A readily accessible for inspection, servicing, and similar requirements.

It is to be noted that the cover members 66 and 67 are thus assembled in oppositely disposed positions relative to the wall structure 1 and will thus permit the screw members 55 to be assembled without interference with the placement and removal of said cover members 66 and 67.

Also it is to be noted that to secure the cover members 66 and 67 in position, a plurality of screws 73 may be assembled through suitable openings in the cover members 66 and 67 to engage the threaded holes 74 in the wall portions of the main support member of the head assembly A.

The belt housing assemblies B and C comprise the tubes or tubular members 75 and 79 which extend telescopically within and are secured to the hub members 76 provided with the flanges 77, which are secured to the under surface of the flange 2 of the head assembly A by the screws 78, the hubs 76 being secured to the upper ends of the tubular members 75 and 79 by welding, brazing, soldering or similar means.

The lower ends of the tubular members 75 and 79 are adapted to threadably engage within the end members 80 so that the maximum diameter of the end members 80 will be substantially flush with the outside diameter of the tubular members 75 and 79.

The end members 80 are provided with conical surfaces 81 and 82 to give them a tapered or pointed appearance as well as to render them adaptable for readily mounting a bag over them for placement over a garment, as hereinafter more fully disclosed.

The hook member 83 is mounted within the end of the end members 80 at their extreme lower sides, the hook members 83 having a shank portion extending through the end wall of the end members and being secured therein by riveting, as at 84 in Fig. 1.

At the lower end of each of the tubular members 75 and 79 adjacent the end members 80 is a pulley 85 having a V-shaped groove 86 which is rotatably supported on the shaft 87, as disclosed in Figs. 28 and 29, the pulley 85 being provided with the bushing 88 which is of an oil-less type for supporting the pulley 85 on the shaft 87.

The shaft 87 is provided with the head portion 89 for mounting in one side of the wall of the bushing 165 adjustably and slidably mounted in the tubular members 75 and 79, the shaft 87 further being provided with the shouldered or extension portion 90 for threadably engaging the opposite wall of the bushing 165.

The bushings 165 are each provided with the extensions 166 which extend through the bushings 167 which are adjustably and threadably mounted in the tubular members 75 and 79, the bushings 167 each being provided with spanner holes 168, the extensions 166 being secured to the bushings 167 by the nuts 169 to permit the bushings 167 to be rotated without rotating the bushings 165 to permit longitudinal movement of the bushings 165 in the tubular members 75 and 79 to adjust the tension of the belt members 94 and 95 when the end members 80 have been removed. The bushings 165 are prevented from turning or rotating by the screws 170 mounted in the tubular members 75 and 79 and engaging the grooves 171 in the bushings 165.

The shafts 39 on which are mounted the spiral beveled gears 31 and 32 are provided with the extension portions 91 which are provided at their outer ends with shoulder portions for engaging and supporting the pulleys 92, the pulleys 92 being fixedly secured thereon and retained by the nuts 93 as disclosed in Fig. 3, one only of said pulleys 92 being disclosed in Fig. 3, it being understood that each of the shafts 39 are provided with a pulley 92 located substantially in alignment with the axis of the tubular members 75 and 79.

The pulleys 92 are provided with the V-shaped grooves 86. The belt members 94 and 95 are provided with the inclined sides 96 to engage and fit the V-shaped grooves 86 of the pulleys 85 and 92, the belts 94 and 95 respectively being 75

adapted to extend endlessly and be driven within the tubular members 75 and 79.

The belts 94 and 95 are provided with a plurality of clips 97 as disclosed in detail in Figs. 9 and 10, the clips 97 being each provided with a flat shank portion 98 which has a pointed end 99, as indicated by the dotted lines in Fig. 10, the pointed end 99 being adapted to pierce and extend through the belt members 94 and 95, at 10 the desired spaced locations, the pointed ends 99 being adapted to be bent over as at 100 in Fig. 9 to lock the clips 97 in a secured position relative to the belts 94 and 95, the portion 100 being adapted to fit within the depression 101 of 15 the belt members 94 and 95.

The clips 97 are each made of resilient material and are each provided with curved portions 102 which are adapted to normally engage the outer surface of the belt members 94 and 95 20 due to the resilient characteristics of the clips 97, the curved portions 102 being adapted to be displaced away from the outer surface of the belts 94 and 95 when a bag 103, such as used for enclosing a garment, is inserted between the curved portion 102 of the clips and the outer surface of the belts 94 and 95, a portion of the bag being disclosed in Fig. 9 to show its clamped position between the portion 102 of the clip and the outer surface of the belt 94.

30 The curved portion 102 of the clips 97 is further extended to provide the rounded end 104 which normally would be always above or removed from the outer surfaces of the belts 94 and 95, as disclosed by the dotted lines 105 in Fig. 9, thus resulting in the rounded end 104 being always positioned away from the outer surface of the belts 94 and 95 even when the portion 102 is in engagement with the outer surfaces of the belts as when the bag 103 is not being clamped by the clip 97, thus preventing any interference in placing the bag 103 under the clip 97 and insuring that the bag 103 when placed beneath the clip 97 will contact only the inside surface of the curved portion 102.

45 Also the curved end 104 will always be positioned below the maximum outer surface of the clip 97 to facilitate the quick placement of the bag 103 over the ends of the tubular members 75 and 79 and the remainder of the clips 97 which may project out of the tubular members 75 and 79.

It is to be noted that the tubular members 75 and 79 will each be provided with the slot or opening 105 extending substantially from the lower ends of the hubs 76 to the upper ends of the end members 80, the slits or openings 105 permitting the clips 97 to be conveyed by the belts 94 and 95 longitudinally of the slots or openings 105 and to extend therethrough and to be exposed on the outside of the tubular members 75 and 79 to facilitate the placement of the bag 103 over the outside of the tubular members 75 and 79 and between the curved portion 102 of the clips 97 and the outer surfaces of the belts 94 and 95.

60 In preparing to support the bag 103 in position for placement over a garment member, the bag 103 is telescopically placed around one of the tubular assemblies B or C as desired and in accordance with the length of the garment and with a consequent length of bag 103 to fit the garment.

70 Thus if the garment to be bagged is relatively short the bag 103 is placed around the tubular assembly B, and in a similar way if the bag 103 is

of greater length, the bag 103 will then be placed telescopically around the tubular assembly C, the bag 103 being indicated by the dotted lines 106 in Fig. 2, as being placed on the tubular assembly B, the bag 103 in the indicated position 106 being disclosed as having been inserted between the curved portion 102 of one of the clips 97 and the outside surface of the belt 95 so that with the operation of the worm 11 by the electric motor assembly D, the worm gear 12 will be revolved, which will in turn revolve the shaft 19 together with the spiral bevel gears 21 and 22, which will in turn cause the pulleys 92 to revolve, this in turn causing the belts 94 and 95 to be operated which will pull or raise the bag 103 upwardly 15 from its indicated position at 106 in Fig. 2 to a position as indicated by the full lines 107, Fig. 4, and in which position the bag 103 has been hoisted or raised to its uppermost position in which it is held by clip mechanism as more fully hereinafter 20 described.

The bag 103 when in the position as indicated by the full lines 107, Fig. 4, is now suspended above the lower end of the tubular assembly B and the garment 108, which is represented as being a gentleman's suit with a coat thereof on the outside, the garment 108 being conventionally mounted on a hanger member 109 which is supported on the hook member 83 of the tubular assembly B, and the bag 103 in the position, as 30 indicated by the full lines 107, Fig. 4, is now ready to be pulled downwardly to enclose and extend around and over the garment 108 sufficiently to allow the hanger 109 to extend above the upper end of the bag 103 to allow the operator to remove the garment 108 and the hanger 109 from the hook 83 of the tubular member B, the garment 108 now being bagged ready for delivery.

In order to facilitate the control of the operation of my bagging machine, I provide means for 40 controlling its operation by a minimum of effort by the operator. This control mechanism will now be described.

As the bag 103 is conveyed upwardly by the belts 94 or 95 to its uppermost position as disclosed in Figs. 4 and 7, the upper end portion of the bag 103 will be forced between the outer surface of the tubular members 75 or 79 and the inner surfaces of the curved portions 110 of the clips 111 which are secured to the surfaces 112 of the walls of the tubular members 75 or 79 in oppositely disposed positions relative to the slots or openings 105 of the tubular members 75 or 79, the clips 111 being fixedly secured by the screws 113, the clips 111 being provided with rounded ends 114 similar to the rounded ends 104 of the clips 97. It is to be noted that the clips 97 will travel past the clips 111 and leave the bag 103 suspended at the upper end of its travel as disclosed by the full lines 107, Fig. 4, the clips 111 being resiliently 60 displaced by the bag 103 to allow the bag 103 to be pulled or conveyed to its clamped position under the fixed clips 111, thus allowing the clips 97 to pull away from the bag 103. As the bag 103 reaches the upper end of its travel, the upper 65 end portion of the bag 103 engages the levers 115 and 116 which are pivotally mounted on the shaft or pin 117, the levers 115 and 116 being automatically moved from the position indicated by the full lines, Fig. 7, to the position indicated by the dotted lines 118, Fig. 7.

The levers 115 and 116 are provided with the curved or depressed surface 119 for engaging the upper end portion of the bag 103, the lever 116 being shown in detail in Figs. 18 and 19.

The blocks 120 and 120A are constructed of material having electrical insulation characteristics and are formed with cylindrical surfaces 121 to engage and fit the inside cylindrical surface of the tubular members 75 and 79, the blocks 120 and 120A being supported in the tubular members 75 and 79 by the shafts or pins 117 passing through the holes 121C of said blocks 120 and 120A, the shafts or pins 117 having one of its ends 10 122 threadedly engaging a wall portion of the tubular members 75 and 79 while the other end is provided with a head 123 which fits within the countersunk portion 124 in an opposite wall portion of the tubular members 75 and 79. The blocks 120 and 120A are each provided with the bosses 125 and 126 which are adapted to engage with and form stop members for limiting the movements of the levers 115 and 116.

The levers 115 and 116 are each provided with a square hole 127 therethrough for receiving the square hub 128 of the bushings 129 which are also provided with the bores 130 which engage and form bearings on the shaft or pin 117, the bushings 129 each being further provided with the tongues or key portions 131 which extend within and form a driving connection with the grooves or keyways 132 in the ends of the hub portion 133 of the lever member 134, the hub portion 133 of the lever member 134 being provided with the bore 135 which forms a bearing on the shaft or pin 117.

It is also to be noted that the blocks 120 and 120A, the levers 115 and 116, and the lever member 134 may be constructed as molded members from materials having electrical insulation characteristics.

It is also to be noted that the hub portion 133 of the lever member 134 spaces the bushings 129 together with the levers 115 and 116 in their operative positions which in turn space the blocks 120 and 120A against the opposite wall portions of the tubular members 75 and 79.

Also any movements of the levers 115 and 116 will be transmitted through the bushings 129 to the lever member 134 and in a reverse manner any movement of the lever member 134 will be transmitted through the bushings 129 to the levers 115 and 116.

The lever members 134 are each provided with the hole 136 for receiving the rivets 137 which secure the ends 138 of the rods 139 to the lever members 134, the rods 139 extending longitudinally of the tubular members 75 and 79 to connect with the button or handle members 140 which are provided with the knurled surfaces 140A and are slidably mounted adjacent the slots 141 in the wall portions of the tubular members 75 and 79, the slots 141 being located adjacent the lower end portions of the tubular members 75 and 79 to provide convenient positions for the operation of the handle or button members 140 by means of the threaded holes 142.

Also it is to be noted that the button or handle members 140 will be located adjacent the side surfaces of the tubular members 75 and 79 in positions which will not interfere with the telescopic movement of the bag 103 over the tubular members 75 and 79 as disclosed in Fig. 6.

Figs. 26 and 27 disclose a terminal member 143 which is mounted in the lever member 116 as by molding the material of the lever member

118 around it, Fig. 19 disclosing the terminal member 143 as having been cast in the material of the lever member 116.

The terminal member 143 is provided with the enlarged portion 144 which extends on each side of the terminal member 143 and has a spherical shape, the enlarged portion 144 being adapted to extend between and forming an electrical connection with the terminal members 145 and 146.

Figs. 22 and 23 disclose a detailed view of the terminal member 145 which is adapted to be mounted in the block 120.

Figs. 24 and 25 disclose the recess 121A for receiving the terminal member 145 which is constructed of suitable material to form electrical engagement with the enlarged portion 144 of the terminal member 143, the terminal member 145 being secured in the recess 121A by the screw 154 to the terminal 152 which engages the terminal member 153.

The terminal member 146, as disclosed in Figs. 6, 7 and 8, is provided with an offset portion 147 which is adapted to electrically engage one side of the enlarged portion 144 of the terminal member 143, the terminal member 146 being provided with the flange portion which is secured by means of the screw 148 and which is adapted to engage the terminal member 149 which is mounted in the recess 121B of the block 120.

It is also to be noted that the terminal member 150, as disclosed in Fig. 7, which is connected to the cable 5, is also secured by the screw 148 in electrical connection with the terminal member 146, the cable 5 being electrically connected, as above described, with the electric motor assembly D.

In a similar way the cable 151 is provided with the terminal member 152 which is electrically connected to the member 145, which is secured in the recess 121A of the block 120 by the screw 154, the screw 154 thus providing an electrical connection between the terminal member 145 and the terminal member 152 which is adapted to engage an opposite side of the enlarged portion 144 of the terminal member 143.

It is to be noted that the terminal member 152 will be located in the recess 155 of the block 120, the recess 155 being formed between the side wall portions of the block 120 and the inside surface of a wall portion of the tubular members 75 and 79, the recess 155 being closed by the insulator 155A mounted in the recess 155B and thus permitting the cable 151 to extend upwardly through the recess 155 and through a suitable opening 75A in the wall portions of the tubular members 75 and 79, as disclosed in Fig. 3, and to further extend, as desired, for electrical connection with the source of supply of electric current for operating the electric motor assembly D which it utilizes for driving the mechanism of my garment bagging machine.

It is to be noted that each of the belt housing assemblies B and C will be provided with one of the switch mechanisms above described and which are adapted to be operated by the handle or button members 140, each of the switch assemblies in each of the belt housing assemblies B and C being connected with the electric motor assembly D and to the source of supply of electric current, thus permitting the operation of the garment bagging machine to control the operation of the electric motor assembly D, and the mechanism driven thereby from a point on each of the belt housing assemblies B and C in ac-

cordance with the position and convenience of the operator.

The speed of travel of the endless belts 94 and 95 may be determined by the selection of the desired ratios between the worm 11 and the worm gear 12 and also between the pair of gears 21 and 22 and the pair of gears 31 and 32 as well as by the design of the electric motor assembly D.

It is now to be noted that I have provided an invention that will provide economical operation by a considerable saving in time in the application of protective means such as bagging, etc., to any kind of garments in such establishments as laundries, dry cleaning establishments, household institutions, department stores and similar establishments or institutions or places of business.

In operation, it will be assumed that the garment bagging machine is at rest, and with the electric motor assembly D not operating to drive any of the mechanism of the garment bagging machine. As the operator desires to begin the operation of bagging a garment, the operator will select one of the handle or button members 140 on either of the belt housing assemblies B and C and by manipulating or slidably moving the button or handle member 140 upwardly in its slot 141, the rod 139 will cause the lever 134 to move upwardly, thus pivotally actuating the hub portion 133 which will rotate the bushing members 129 which in turn will cause the ends of the lever members 115 and 116, each having a depressed surface 119 therein, to move downwardly from the position as indicated by the dotted lines 118 in Fig. 7 to the position as disclosed by the full lines of said portions of said levers 115 and 116 and at the same time the terminal member 143 in the lever member 116 will be moved upwardly to cause the enlarged portions 144 of the terminal member 143 to engage the terminal member 145 and the flange portion 147 of the terminal member 146, thus establishing an electrical connection between the terminal members 145 and 146 to cause a flow of electric current through the cable 151 and then through the cable 5 to the electric motor assembly D which will start its operation.

The operation of the electric motor assembly D will drive the worm 11 which in turn will drive the worm gear 12 which will cause the spiral bevel gears 21 and 22 to drive the spiral bevel gears 31 and 32 which will cause the pulleys 92 to rotate, the operation of the pulleys 92 causing the belt members 94 and 95 to operate endlessly around both of the sets of pulleys comprising the pulleys 92 and 85.

The operation of the belts 94 and 95 will cause the clips 97 to travel upwardly adjacent the slots 105 thus exposing the clips 97 as they travel upwardly through the slots 105 so that the operator may place a bag 103 telescopically around either of the belt housing assemblies B or C as desired, one side of the upper end portion of the bag being inserted between the inside surface of the curved portion 102 of one of the clips 97 and the outside surface of one of the belts 94 or 95 as the selected clip 97 moves around the pulleys 85 into the lower portion of the opening 105.

Then with the bag 103 clipped between the curved portion 102 of one of the clips 97 and the outside of one of the belts 94 or 95 as the case may be, the bag 103 will be conveyed upwardly from substantially its position as indicated by the dotted lines 106, in Fig. 2, to the position indicated

by the full lines 107, Fig. 4, and as the bag 103 approaches a position adjacent the upper end of the belts 94 or 95, one side of the upper end of the bag portion will be conveyed under the curved portions 110 of the clips 111 which will prevent the bag 103 from being conveyed further and will hold the bag 103 in the position as indicated by the full lines 107, Fig. 4, until such time as the operator is ready to place the bag 103 over the garment.

At the same time, as the upper end portion of the bag 103 is moved under and clamped by the curved portions 110 of the clips 111, the upper end portion of the bag 103 will engage the depressed surfaces 119 of the levers 115 and 116 which will cause the levers 115 and 116 to move from the position as indicated by the full lines thereof in Fig. 7 to the position as indicated by the dotted lines 118 which will move the enlarged portions 144 of the terminal member 143 from an engaged position between the terminal members 145 and 146, thus breaking the circuit and preventing the electrical current from flowing from the cable 151 through the cable 5 to the electric motor assembly D, thus stopping the operation of the electric motor assembly D.

The operator now places the garment 108, which is conventionally supported on a hanger member 109, on one of the hook members 83 depending, of course, upon which of the belt housing assemblies B or C is desired for supporting the bag 103.

Now the operator takes the bag 103 and by a downward pull thereon releases the bag 103 from its clamped position between the curved surfaces 110 of the clips 111 which allows the bag to be lowered and telescopically mounted over and around the garment 108 with the hanger member 109 extending through the upper portion of the bag 103. The garment 108 is now enclosed in its bag and is ready for delivery upon removal from the hook member 83.

When the operator is ready to place another bag over a garment the operation is repeated by starting the motor assembly D as above described.

I claim:

1. In a garment bagging machine, the combination of a bracket, an electric motor assembly mounted on said bracket and electrically connected with a source of supply of electrical current, gear means, a pulley rotatably mounted and driven by said gear means, a tubular member supported by said bracket, a pulley rotatably mounted adjacent the lower end of said tubular member, said tubular member being provided with a slot extending longitudinally thereof, an endless belt movably mounted on said first mentioned and said second pulleys, a plurality of clips mounted on said endless belt and extending through said slot of said tubular member, said clips being adapted to clamp a bag against said endless belt to permit said endless belt to convey said bag to a position for placement over a garment, means for supporting said garment from the lower end of said tubular member, clip members supported on said tubular member and adapted to clamp said bag after it has been conveyed to said position for placement over said garment, switch means engaged by said bag to stop the operation of said electric motor assembly, adjustable means supporting said bracket from a wall structure, and cover means on said bracket for enclosing said electric motor assembly together with its operatively connected mechanism mounted on said bracket.
2. In a garment bagging machine, the combi- 75

nation of a bracket, a tubular member supported by said bracket and provided with a slot in its side walls, said slot extending longitudinally of said tubular member, an endless belt movably mounted in said tubular member, a plurality of clips mounted on said endless belt and adapted to hold a bag while being conveyed by said endless belts to a position for placement over a garment, clip means mounted on said tubular member and adapted to hold said bag after it has been conveyed to said position for placement over said garment, means for supporting said garment from said tubular member in a position to receive said bag, and means for driving said endless belt.

3. In a garment bagging machine, the combination of a bracket, a tubular member supported from said bracket and provided with a slot extending through and longitudinally of a side wall thereof, belt mechanism movably mounted in said tubular member and provided with means for clamping a bag for a garment while said bag is being conveyed by said belt mechanism, said means of said belt mechanism extending within said slot of said tubular member, clamp means mounted on said tubular member, and adapted to hold said bag after said bag has been conveyed by said belt mechanism, and means for driving said belt mechanism.

4. In a garment bagging machine, the combination of a bracket, a tubular member supported by said bracket and provided with a slot extending longitudinally thereof, a belt mechanism movably mounted in said tubular member and adapted to hold and convey a bag to a position for placement over a garment, clip means for holding said bag after it has been conveyed by said belt mechanism to said position for placement over said garment, means for driving said belt mechanism, and means for automatically stopping said first mentioned means when said bag has been conveyed to said position.

5. In a garment bagging machine, the combination of a bracket, a tubular member supported by said bracket and provided with a slot extending longitudinally thereof, belt mechanism movably mounted in said tubular member and adapted to hold and convey a bag to a position for placement over a garment, clip means for holding said bag after it has been conveyed by said belt mechanism to said position for placement over said garment, means for driving said belt mechanism, and switch mechanisms on said tubular member for starting and stopping said means for driving said belt mechanism.

55. 6. In a garment bagging machine, the combination of an endless belt movably mounted and adapted to convey a bag to a position for placement over a garment, a tubular member enclosing said endless belt, means supported by said tubular member for holding said bag in its position for placement over said garment, means for driving said endless belt, and a switch mechanism for controlling the starting and stopping of said means for driving said endless belt.

65. 7. In a garment bagging machine, the combination of an endless belt movably mounted and adapted to convey a bag to a position for placement over a garment, means for holding said bag in its position for placement over said garment, means for driving said endless belt, and a switch mechanism for controlling the starting and stopping of said means for driving said endless belt, said switch mechanism being adapted to be manually operated for starting said means for driving said endless belt, said switch mech-

anism being engaged and actuated by said bag to stop said means for driving said endless belt.

8. In a garment bagging machine, the combination of a housing member provided with a lubricant tight chamber, torque transmitting mechanism mounted to operate in said lubricant tight chamber, power driving means mounted on said housing member and operatively connected with said torque transmitting mechanism, a pulley rotatably mounted and driven by said torque transmitting mechanism, a tubular member supported by said housing member, a second pulley rotatably mounted in said tubular member, an endless belt movably supported on said first mentioned and said second pulleys and adapted to convey a bag longitudinally of said tubular member to a position for placement over a garment, and clip means for holding said bag in said position for placement over said garment.

9. In a garment bagging machine, the combination of a housing member provided with a lubricant tight chamber, torque transmitting mechanism mounted to operate in said lubricant tight chamber, power driving means mounted on said housing member and operatively connected with said torque transmitting mechanism, a pulley rotatably mounted and driven by said torque transmitting mechanism, a tubular member supported by said housing member, a second pulley rotatably mounted in said tubular member, an endless belt movably supported on said first mentioned and said second pulleys and adapted to convey a bag longitudinally of said tubular member to a position for placement over a garment, means for adjustably moving said second pulley to adjust the tension of said endless belt, clip means for holding said bag in said position for placement over said garment, and a switch mechanism for starting said power driving means, said switch mechanism being adapted to be actuated, by engagement with said bag, to stop said power driving means.

10. In a garment bagging machine, the combination of a housing member provided with a lubricant tight chamber, said housing member being provided with shoulder portions extending therearound, torque transmitting mechanism mounted to operate in said lubricant tight chamber, power driving means mounted on said housing member and operatively connected with said torque transmitting mechanism, a pulley rotatably mounted and driven by said torque transmitting mechanism, a tubular member supported by said housing member, a second pulley rotatably mounted in said tubular member, an endless belt movably supported on said first mentioned and said second pulleys and adapted to convey a bag longitudinally of said tubular member to a position for placement over a garment, clip means for holding said bag in said position for placement over said garment, and cover members mounted on said shoulder portions of said housing member and enclosing said power driving means, said first mentioned pulleys, and said lubricant tight chamber of said housing member.

11. In a garment bagging machine supported by a horizontal wall structure, the combination of a housing member provided with a pair of boss portions each having bores therethrough, an endless belt movably supported by said housing member and adapted to convey a bag to a position for placement over a garment, power means driving said endless belt, clip means for holding said bag in said position for placement over said garment.

- over said garment, shaft members extending through said bores of said pair of boss portions of said housing member, means for securing said shaft members to said horizontal wall structure, and means for fastening said housing member to said shaft members in a plurality of adjusted positions.
12. In a garment bagging machine supported by a vertical wall structure the combinations of 10 a housing member provided with a pair of boss portions each having bores therethrough, an endless belt movably supported by said housing member and adapted to convey a bag to a position for placement over a garment, power means 15 driving said endless belt, clip means for holding said bag in said position for placement over said garment, shaft members extending through said bores of said pair of boss portions of said housing member, means for fastening said housing member to said shaft members in a plurality of 20 adjusted positions, a bracket member, means for securing said bracket member to said vertical wall structure, and means for securing said shaft members to said bracket member.
- 25 13. In a garment bagging machine, the combination of a head structure, a tubular member supported by said head structure, an endless belt movably mounted in said tubular member and provided with means extending through said 30 tubular member for clamping a bag while being conveyed by said belt to a position for placement over a garment, power means supported by said head structure and driving said belt, clip means for holding said bag in said position for placement 35 over said garment, and hook means at the end of said tubular member for supporting said garment.
14. In a garment bagging machine, the combination of a head structure, a tubular member supported by said head structure, an endless belt 40 movably mounted in said tubular member and provided with means extending through said tubular member for clamping a bag while being conveyed by said belt to a position for placement over a garment, power means supported by said head structure and driving said belt, clip means for holding said bag in said position for placement 45 over said garment, hook means at the end of said tubular member for supporting said garment, and switch mechanism mounted on said tubular member for starting and stopping said power means.
15. In a garment bagging machine, the combination of a head structure, a tubular member supported by said head structure, an endless belt 50 movably mounted in said tubular member and provided with means extending through said tubular member for clamping a bag while being conveyed by said belt to a position for placement over a garment, power means supported by said head structure and driving said belt, clip means for holding said bag in said position for placement 55 over said garment, hook means at the end of said tubular member for supporting said garment, switch mechanism mounted on said tubular member for starting and stopping said power means, said switch mechanism being provided with lever members adapted to be engaged by said bag, as said bag is conveyed to said position 60 for placement over said garment, the engagement of said lever members by said bag operating said switch mechanism to stop said power means, and a button member movably supported adjacent the lowermost end portion of said tubular member and connected with said switch mechanism

to cause said switch mechanism to start said power means.

16. In a garment bagging machine, the combination of a head member, a tubular member supported by said tubular member, and endless belt member movably mounted in said tubular member and provided with means for clamping a bag while said bag is being conveyed by said endless belt to a position for placement over a garment, power means supported by said head member and driving said endless belt, clip means for holding said bag on said tubular member after said bag has been conveyed to said position for placement over said garment, and switch mechanism mounted on said tubular member for starting and stopping said power means, said switch mechanism being provided with a button member located adjacent the lower end of said tubular member, said button member being connected with said switch mechanism to permit manual 20 operation thereof.

17. In a garment bagging machine, the combination of a head structure, a tubular member supported by said head structure, an endless belt movably mounted in said tubular member, an electric motor assembly supported by said head structure and driving said endless belt, clip means mounted on said endless belt and adapted to hold a bag being conveyed to a position for placement over a garment, a second clip means 30 mounted on said tubular member for holding said bag in said position for placement over said garment, a shaft mounted in said tubular member, a pair of block members mounted on said shaft in said tubular member and each provided 35 with stop members, a pair of levers pivotally mounted on said shaft and adapted to engage said stop members of said block members, said pair of levers being adapted to be pivotally moved by engagement with said bag, one of said pair of levers being provided with a ball portion, bushing members mounted in and supporting said pair of levers on said shaft, a pair of terminals mounted on one of said pair of block members and adapted to be engaged by said ball portion of one 40 of said pair of lever members, means for electrically connecting one of said pair of terminal members with a source of supply of electric current, means for electrically connecting the other of said pair of terminals with said electric motor assembly, a lever member pivotally mounted on 45 said shaft and driving said pair of bushings, and a button member slidably mounted on said tubular member and operatively connected with said last mentioned lever member.

18. In a garment bagging machine, the combination of a tubular member, a head structure supporting said tubular member, a pair of blocks having cylindrical surfaces engaging the inside surfaces of said tubular member, a shaft mounted in said tubular member and supporting said 60 pair of blocks, a pair of lever members pivotally mounted on said shaft, one of said lever members being provided with a terminal portion, a pair of terminal members mounted on one of said pair 65 of blocks and adapted to be engaged by said terminal portion of one of said pair of lever members, a third lever member mounted on said shaft and adapted to movably operate said pair of lever members, a belt movably mounted in said tubular member and adapted to convey a bag to a 70 position for placement over a garment, said bag being adapted to engage and movably operate said pair of lever members, clip means mounted on said tubular member to hold said bag in said 75

position for placement over said garment, an electric motor assembly mounted on said head structure and adapted to drive said belt, means for connecting one of said pair of terminal members with a source of electric current, means for electrically connecting the other of said pair of terminal members with said electric motor assembly, and a button member operatively connected with said third lever member.

10. 19. In a garment bagging machine, the combination of an endless belt movably mounted and adapted to convey a bag to a position for placement over a garment, power means for driving said belt, clamp means for holding said bag in said position for placement over said garment, and a switch mechanism suitably mounted to start and stop said power means.

20. In a garment bagging machine, the combination of a support structure, a tubular member mounted on said support structure, an endless belt movably mounted in said tubular member and adapted to convey a bag telescopically of said tubular member to a position for placement over a garment, power means mounted on said support structure and adapted to drive said endless belt, clamp means for holding said bag in said position for placement over said garment, switch mechanism mounted on said tubular member adjacent said clamp means for starting and stopping said power means, said switch mechanism being adapted to be operated by engagement with said bag to stop said power means, and a movably mounted member adjacent the lowermost end of said tubular member and connected with said switch mechanism to permit an operator of the garment bagging machine to start said power means by moving said movably mounted member.

21. In a bagging machine, the combination of an endless conveyor means for conveying a bag to a position for placement over a garment or similar object, said bag being conveyed telescopically over said endless conveyor means, means for holding said bag in said position, and means for driving said endless conveyor means.

22. In a garment bagging machine, the combination of a pulley rotatably mounted, means for driving said pulley, a second pulley rotatably mounted, an endless belt member movably supported on said first mentioned and said second pulleys and adapted to convey a bag to a position for placement over a garment or similar member, said bag being conveyed telescopically relative to said endless belt member and said pulleys, and means for holding said bag in said position for placement over said garment.

23. In a garment bagging machine, the combination of a tubular member suitably supported, a pulley rotatably mounted and supported adjacent one end of said tubular member, means for driving said pulley, a second pulley rotatably mounted in said tubular member, an endless carrier member engaging and driven by said pulleys, said endless carrier being adapted to convey a bag longitudinally of said tubular member to a position for placement over a garment, support means for holding said bag in said position for placement over said garment, and means for controlling the operation of said driving means, said last mentioned means being actuated by engagement with said bag.

24. In a garment bagging machine, the combination of a housing, a conveyor means movably supported by said housing and adapted to convey a bag to a position for placement over a garment or similar object, means for driving said conveyor means, clip means for holding said bag in said position for placement over the garment or similar object, shaft means engaging said housing, adjustable means securing said shaft means and said housing together, and means for securing said shaft means to a wall or similar supporting structure.

25. In a garment bagging machine, the combination of a housing, a conveyor means movably supported by said housing and adapted to convey a bag to a position for placement over a garment or similar object, means for driving said conveyor means, clip means for holding said bag in said position for placement over the garment or similar object, shaft means engaging said housing, adjustable means securing said shaft means, and a bracket member secured to said shaft means, said bracket member being provided with a flange portion adapted to be secured to a wall or similar supporting structure extending substantially in a vertical plane.

26. In a garment bagging machine, the combination of an endless conveyor member movably supported, a tubular member suitably supported and extending around said endless conveyor member, means supported by said endless conveyor member for securing a bag while being conveyed by said endless conveyor member to a position for placement over a garment, means for driving said endless conveyor member, means supported adjacent an end of said tubular member for supporting said garment, and means for holding said bag in said position of placement over said garment.

HARLYN D. OLIVER.
